UNITED STATES PATENT OFFICE.

HERRMAN REES, OF NEW YORK, N. Y., ASSIGNOR TO LOUIS J. REES AND HENRY P. REES, BOTH OF SAME PLACE.

EAR-RING.

SPECIFICATION forming part of Letters Patent No. 421,433, dated February 18, 1890.

Application filed March 1, 1889. Serial No. 301,644. (No model.)

To all whom it may concern:

Be it known that I, HERRMAN REES, of the city, county, and State of New York, a citizen of the United States, have invented certain 5 new and useful Improvements in Ear-Rings, of which the following is a specification.

This invention relates to certain improvements in ear-rings of that class in which the ear-wire is retained on the lobe of the ear by 10 means of suitable fastening devices.

In the accompanying drawings, Figure 1 represents a side elevation of my improved ear-ring, shown partly in section; and Fig. 2 is a vertical transverse section of the same on 15 line *y y*, Fig. 1.

Similar letters of reference indicate corresponding parts.

Referring to the drawings, A represents the ear-wire of my improved ear-ring, and B the 20 setting of a diamond or other precious stone which is applied to the ear-wire. The upper backwardly-bent end of the ear-wire A is passed through a hole in the lobe of the ear and through an eye *d'* in a locking-bar C, that 25 is hinged to the lower end of the ear-wire A.

A keeper e is pivoted to a stud f on the locking-bar C, below the eye *d'*, said keeper being provided with an arc-shaped slot e', which is enlarged at one end, so as to permit the upper end of the ear-wire to enter into said slot 30 after the same has passed through the eye *d'* of the locking-bar. The end of the ear-wire A is provided with a contracted neck, forming a knob e² at its upper end, which contraction is engaged by the slot of the keeper e, and when the keeper is swung into the position shown in Fig. 2 the neck is held in the narrow part of the slot and the ear-wire is locked. When the keeper is swung in opposite 35 direction until the enlarged end of the slot is in line with the end of the ear-wire A,

the locking-bar C can be swung on its hinged connection in downward direction into the position shown in dotted lines in Fig. 1. In this position of the locking-bar the ear-wire 45 can be readily removed from the ear or applied thereto, as the case may be. For applying the ear-ring, the ear-wire A is passed through the perforation in the lobe of the ear, the locking-bar C moved in upward direction, so that the eye at its upper end passes over the upper end of the ear-wire A, after 50 which the pivoted keeper e is applied to the end of the ear-wire, and thereby the ear-ring retained on the lobe of the ear.

My improved ear-ring has the advantage 55 that it is retained firmly in position on the lobe of the ear, that the setting is suspended close to the ear, and that the ear-ring can be applied to or detached from the ear with great facility.

Having thus described my invention, I claim as new and desire to secure by Letters Patent—

An ear-ring comprising a curved ear-wire 65 having a knob at its upper end, a locking-bar hinged to the lower end of said ear-wire and provided with an eye for engaging the upper end thereof, said bar being provided with a laterally-projecting stud below said eye, and 70 a keeper pivoted on said stud and provided with an arc-shaped slot for engaging said knob, one end of said slot being enlarged, substantially as described.

In testimony that I claim the foregoing as 75 my invention I have signed my name in presence of two subscribing witnesses.

HERRMAN REES.
